Co-pending U.S. Appl. No. 13/193,243, titled "Culture Bottles with Internal Sensors", filed Jul. 28, 2011.

Primary Examiner — Anhdao Doan

(57) **CLAIM**

The ornamental design of a specimen container, as shown and described.

DESCRIPTION

FIG. 1 is a perspective view of the specimen container showing the design;

FIG. 2 is a front elevation view of the container shown the design of FIG. 1;

FIG. 3 is a top view of the specimen container design shown in FIG. 1;

FIG. 4 is a bottom view of the specimen container design shown in FIG. 1; and,

FIG. 5 is a cross-sectional view of the specimen container design shown in FIG. 1.

The specimen container is intended for use with a microbial detection apparatus and is designed to hold a culture medium and a specimen which is to be analyzed for the presence of microorganisms.
